BOTTLE CARRIER

Lyman C. Gish, Rittman, Ohio, assignor to Packaging Corporation of America, Rittman, Ohio, a corporation of Delaware

Filed Jan. 14, 1960, Ser. No. 2,471

6 Claims. (Cl. 220—115)

This invention relates to cartons made of paperboard or other appropriate sheet material and it is directed particularly to structural and functional modifications of bottle carrier cartons of the type shown generally in the patents of Michael H. Kowal No. 2,692,700, granted October 26, 1954, and No. 2,712,397, granted July 5, 1955, and particularly in applicant's copending application for patent for Bottle Carrier, filed March 12, 1959, Serial No. 798,942, now patent No. 2,996,216, granted August 15, 1961.

In bottle carrier cartons of these types it has been found desirable to provide a central partition member which will extend from the upwardly projecting carrying handle into close proximity to, or against, the bottom wall of the carton in order to prevent contact of the bottles in the two rows thereof arranged longitudinally of the carton at opposite sides of the carrying handle, and it is also desirable to provide transverse partition members which similarly extend downwardly into proximity to the bottom to prevent contact between the bottles forming these rows.

To this end one object of the invention is to provide a bottle carrier carton with this said type of partition members in a form which will permit flatfolding of the carton as is desired and which requires no special manipulation of such partition members for their functional location when the carton is set up for use.

Another object is to provide in an integral sheet material blank parts, defined by cuts and folding scores, which, in the assembled, and ultimately erected, carrier will form the desired central partition, but which form scrap within the area of a blank of the size normally employed for the construction of a carrier of this general type but not provided with such a central partition, and to provide, in addition, elements comprising the said transverse partition members also formed, at least in part, from scrap areas of said blank and adapted to be assembled with the blank.

A further object is to provide the transverse partition members as individual elements, or as integers comprising two of the said members which may be separated into the individual elements during the carton assembling and gluing operation, or as integers of two of the said members in which the said members are defined from each other by lines of fracture to the end that the members of each such last described integer may be simultaneously properly located upon the flat blank and thus maintained during assembly of the blank to ultimate carrier form, but may separate upon such lines of fracture upon erection of the carton for use, the form that the said transverse partition members may take being dictated by choice of the manufacturer and the type of assembling and gluing machine used.

With these and other objects in view, as will be apparent from the following description, the invention comprises a carrier carton, particularly for bottles, and the sheet material elements of a blank for forming such carrier, including a bottom wall, side walls joined to the longitudinal edges of the bottom wall along appropriate folding scores, end wall sections joined to the end edges of the side walls and connected together substantially medially of the bottom wall to provide full end walls spanning the ends of the bottom wall between the side walls, a handle member disposed medially of the bottom

2

and side walls, bottle compartment separator straps arranged in spaced relation to each other and to the end walls and transversely spanning the spaces between and connected with the side walls and handle member, and transverse partition members carried by said compartment separator straps and extending downwardly therefrom into proximity to the bottom wall; and the invention includes, also, a partition member constituting a downward extension of said handle member and serving, with said transverse partition members, to divide the interior of the carrier into a plurality of separate, fully walled cells, said elements, with the exception of said transverse partition members, being formed as integral parts of a single blank of sheet material in which they are defined by cuts and folding scores, all as will be explained hereinafter more fully and finally claimed.

In the accompanying drawings illustrating the invention, in the several figures of which like parts are similarly designated,

FIG. 1 is a plan view of the inner face of a sheet material blank from which the carton of the invention is constructed.

FIGS. 1a and 1b are plan views of one form of the two elements in which the individual transverse partition members for the six-cell carton shown are defined by pre-formed lines of fracture,

FIGS. 1c and 1d are similar plan views of alternative forms of transverse partition members,

FIGS. 2 to 5 are views similar to FIG. 1, but drawn to a smaller scale, showing the progressive steps of assembling, folding and adhesively securing the various parts of the blank, including transverse partition forming elements of the type shown in FIGS. 1a and 1b, prior to its final folding and securing,

FIGS. 6 and 7 show one of the outer faces of the finally flat-folded and secured blank assembled from the parts shown in FIGS. 2 to 5, and

FIGS. 8 and 9 are perspective views of the opposite sides and ends of the erected carrier carton of the assembly of FIGS. 2 to 7, FIG. 9 showing a portion of the carton end wall broken away to expose the interior.

Referring particularly to FIG. 1, it will be seen that the flat blank includes a bottom wall comprising relatively foldable halves 1a and 1b joined along a longitudinal folding score 2, and at the opposite longitudinal edges of this dual bottom wall are side walls 3a and 3b joined to such edges along folding scores 4a and 4b. At the opposite end edges of the side walls 3a and 3b and joined thereto along folding scores 5a, 5a' and 5b, 5b' are end wall sections 6a, 6a' and 6b, 6b' provided, respectively, with complementary connecting flaps 7a, 7a' and 7b, 7b' which may be folded upon their respective folding scores 8a, 8a' and 8b, 8b' so that they may be adhesively secured together in pairs for completing the end walls from the end wall sections 6a—6b and 6a'—6b' when the blank is given its final assembly fold (FIGS. 6 and 7).

Extending outwardly in the blank from the side walls 3a and 3b, and offset longitudinally thereof, are handle members 9a and 9b, respectively, which are defined from their side walls by cuts 10a and 10b and are connected to such side walls by separator straps 11a, 11a' and 11b, 11b' hinged on folding scores 12a, 12a' and 12b, 12b'. The separator straps 11a and 11b are connected to the handle members 9a and 9b on folding scores 13a and 13b, and the separator straps 11a' and 11b' are connected to foldable handle reinforcing and partition forming elements 14a and 14b, respectively, on folding scores 15a and 15b. Cuts 16a, 16a' and 16b, 16b' separate the straps 11a, 11a' and 11b, 11b' from their respective side walls, and cuts 17a and 17b separate the straps 11a' and

11b' from their respective structural elements 14a and 14b.

The handle members 9a and 9b are provided with ultimately mating hand holes 18a and 18b, and the handle member 9b is provided with a finish flap 19 foldable upon a folding score 20 over an extension 21 on the handle member 9a, the thus folded flap 19 being appropriately secured, in the assembled blank, as by adhesive, to the extension 21 to provide a stiffening and reinforcing means for the handle assembly.

All of the elements of the blank thus far described have their structural and functional counter-parts, disclosed in a slightly different form, in the Kowal Patent No. 2,692,700 hereinabove referred to.

Preferably the end wall elements 7a and 7b will be provided with cuts defining ultimately mating and adhesively joined hooks 22a and 22b engageable with an adjacent edge 23 of the bottom wall 1a, 1b to serve in locking the carton in erected condition with its bottom wall portions 1a and 1b in substantially flat coplanar arrangement.

As hereinbefore stated the carrier carton of the invention is preferably provided with a longitudinal center partition extending from the handle portion to the bottom wall of the erected carrier without increasing the usual area of the blank for a carton of this general character. In other words the center partition will be formed from parts of the blank which would normally constitute scrap, and they are so arranged and connected together and to other elements of the carton structure, particularly those forming the end walls and handle member, as not only to produce the desired partition but also to make the whole erected carton stronger and more rigid and the handle member better adapted to support the load of the filled carton. Furthermore, the connection of these partition forming elements to the handle members makes them serve, with the joined handle members, to form a combined partition and handle member.

To this end, that portion of the blank which lies between the proximate ends of the end wall elements 6a and 6b, and which in the assembled blank forms the partition panel 24, is severed upon a cut 25 defining one of its edges 25' and the bottom edge of the end wall element 6b, and upon the cut 23 which forms another one of its edges 26 as well as the aforementioned end edge of the bottom wall elements 1a and 1b. The panel 24 has its third edge separated from the blank by a cut 27 which also forms the bottom edge of the end wall element 6a, and a tab 28 provided by a cut 28', which serves also to define the hook 22a, is joined along a diagonal folding score 29 to the securing flap 7a of the end wall element 6a.

A handle reinforcing element 30 is formed as an extension of the structural element 14b and is foldable therewith upon a folding score 31 aligned with the folding score 12b' of the separator strap 11b'. The structural element 14a is foldable upon a folding score 32 aligned with the folding score 12a' of the separator strap 11a'. The folding scores 31 and 32 define complementary end edges of the handle members 9a and 9b.

Diagonal cuts 33a and 33b which extend between the folding scores 5a', 8a' and 5b', 8b' of the end wall elements 6a' and 6b' respectively, serve to sever these elements for pivotal or hinging movement relative to the handle members 9a and 9b upon erection of the carton to usable form. Similar diagonal cuts 34a and 34b serve to sever the structural elements 14a and 14b from the end wall elements 6a and 6b.

Having reference to FIGS. 1a and 1b, it will be seen that the form of the blanks comprising the elements from which the transverse partition members are provided, and which constitute an example of one preferred embodiment thereof each includes a pair 35a, 35b (FIG. 1a), and 36a, 36b (FIG. 1b), of such members, the members 35a and 35b being separable upon a line of

fracture composed of a cut 37 extending inwardly from its upper edge and a row of spaced perforations 38, and the members 36a and 36b being separable upon a similar line of fracture composed of the cut 39 and row of spaced perforations 40.

These dual elements comprising the transverse partition members 35a, 35b, and 36a, 36b are of such size that they may be formed from the scrap normally discarded in the blanking out of cartons, and it will be noted that at least one of the elements may be formed from the scrap discarded from the space lying between the end wall sections 6a' and 6b' and the adjacent edge of the bottom wall 1a, 1b, FIG. 1.

The procedure for assembling the blank elements of FIGS. 1, 1a and 1b to completed flat-folded form (FIGS. 6 and 7) from which it may be erected to usable carrier form (FIGS. 8 and 9) is preferably in a plurality of successive folding and gluing steps all of which are capable of being performed by known types of automatic machines with no more than the adjustments and substitutions of parts of such machines which are necessary for their adaptation to any special folding and gluing job.

Referring to FIGS. 1 to 7 by which an understanding of the assembly procedure from flat blank to flat-folded and glued carton may be obtained, it will be seen (FIG. 1 and 2) that, with adhesive applied in the areas of the partition straps 11a and 11b substantially as shown by stippling in FIG. 1, the transverse partition elements 35a, 35b and 36a, 36b are affixed thereto with their aforesaid upper edges in substantial alignment, respectively, with the cuts 10a and 10b, and with their lines of cleavage in substantial alignment with, and overlying, the folding scores 12a and 12b as shown in FIG. 2. It will be noted that, although only the partition members 35a and 36a are thus adhesively affixed, the two elements in which these members are comprised will thus be properly positioned for subsequent assembly operations. Next with adhesive applied to the structural elements 14a, 14b and 30, and to the partition straps 11a' and 11b', as shown by the stippling in FIG. 2, the elements 14a, 14b and 30 are folded upon their scores 32 and 31, respectively, over upon, and secured to, the inner faces of the handle members 9a and 9b, respectively, and the straps 11a' and 11b' are folded on their scores 12a' and 12b' over upon, and secured to, the transverse partition members 35b and 36b, respectively, as shown in FIG. 3. Then, with adhesive applied to the stippled areas (FIG. 3) of the flaps 7a and 7b of the end wall sections 6a and 6b, these end wall sections are folded upon their scores 5a and 5b and the flaps 7a and 7b are carried with them and secured, flat-folded upon the elements 14a and 14b (FIG. 4) in the areas of the adhesive applied to these flaps. It will be noted, also, that this folding of the end wall section 6a and its flap 7a carries with it the longitudinal partition panel 24.

Now, the end wall flaps 7a' and 7b' are folded upon their respective folding scores 8a' and 8b' so as to overlie their end wall elements 6a' and 6b' (FIG. 4) and, with adhesive applied to a limited edge area of the flap 7a', and to an exposed portion of the structural element 14a in the area indicated by stippling in FIG. 4, the partition panel 24 is folded upon its diagonal folding score 29 to the position shown in FIG. 5 in which the adhesive applied at the edge of the flap 7a' and on the exposed portion of the element 14a will cause it to adhere to such flap and element.

Thereafter, with adhesive applied to the exposed surfaces of the parts 9a, 21, 7a, 7a', 28 and 14b, and to that edge of the panel 24 which overlies the flap 7a', all as indicated by stippling in FIG. 5, the thus far assembled and secured blank is folded upon the median folding score 2 of the bottom wall 1a—1b to bring the two halves of the blank in register and effect their adhesively secured assembly. Finally, with adhesive applied to the

exposed surface of the finish flap 19, FIG. 6, this flap is folded upon its folding score 20 over, and affixed to, the then underlying extension 21 of the handle member 9a, as shown in FIG. 7, to complete the flat-folded assembly of the carton.

To erect the flat-folded carton to usable form, FIGS. 8 and 9, it is merely necessary to apply pressure to the folded edges A and B, FIGS. 6 and 7, until the carton is squared up, and to engage the adhesively combined hooks 22a-22b of the flaps 7a and 7b with the edge 23 of the bottom wall.

As thus set up it will be apparent that the combined partition and handle member extends medially longitudinally of the carton and its partition-forming portion produced by the panel 24 and portions of the elements 14a and 14b, together with the flaps 7a, 7a' and 7b, 7b' to which they are all adhesively connected, extends to the bottom wall of the carton and serves adequately to separate the rows of bottles at its opposite faces.

Also, during erection of the carton the pivoting of the partition straps 11a, 11a' and 11b, 11b' will carry with them the transverse partition members 35a, 35b and 36a, 36b, respectively, which part from their respective integral elements along the respective lines a cleavage 37-38 and 39-40 due to the pull applied to them as a result of such pivoting of the straps to which they are affixed. Thus, when the carton is erected, these transverse partition members will divide the longitudinal compartments at opposite sides of the longitudinal partition and handle member into three cells each in which the six packaged bottles will be separated from each other by full depth partitions both longitudinally and transversely of the carton, and the disadvantages incident to their contact, such as defacement of labels, noise and the like, obviated.

It will be noted, moreover, that, in the application of adhesive to parts to be joined during the flat-folding assembly of the blank, adhesive is applied only to those areas of the straps 11a, 11a' and 11b, 11b' to which the transverse partition members 35a, 35b and 36a, 36b are attached. Hence, when the carton is squared up these straps are free to assume their functional positions between the side walls 3a and 3b and the opposite faces of the combined partition and handle member by free hinging or pivoting upon their folding scores 12a, 13a; 12a', 15a, 12b, 13b; 12b', 15b, carrying with them their respective transverse partition members, as just previously described.

Obviously, when the hook 22a-22b of the end wall structure is disengaged from the edge 23 of the bottom wall, the carton may be re-collapsed to flat-folded condition, if desired.

Due to the rigid assembly of the elements of the longitudinal partition member, and its connection with the end wall flaps 7a, 7a' and 7b, 7b' which, in the erected carrier (FIGS. 8 and 9), form parts of this partition member, and due, also, to the rigid, multiple-reinforced nature of the handle member, the carrier is of extremely sturdy construction and serves well for carrying the relatively heavy load of bottled beverages or the like for which it is designed.

Moreover, in view of the fact that the carrier of the invention, while embodying a combined partition and handle member of full length and height, and full depth transverse partition members applied to the partition straps, can be constructed from a sheet material blank of relatively no greater area than that required for similar carriers which do not provide these several full partition elements, and may be produced on automatic machinery of known type generally adapted for the manufacture and assembly of such last named carriers, the carrier of the invention has advantages of function and economy of production which are attractive to packagers of bottled goods.

Although the use of transverse partition members

formed in the integer type shown in FIGS. 1a and 1b has advantages, particularly as related to the functioning of a given type of assembling and gluing machine, as hereinbefore particularly described, these members may be so formed as to adapt them to other modes of assembly with the primary carton blanks and to the functioning of other types of assembling and gluing machines.

For example, as shown in FIG. 1c, the transverse partition members may be in the form of separate cards 10 individually and simultaneously, or successively, applied, by gluing, to the partition straps 11a, 11a' and 11b, 11b', and, as shown in FIG. 1d, these members may be formed from cards which are double the size of the individual members and may be separated along medial lines m by the assembling and gluing machine prior to, or simultaneously with, their glue application to the respective partition straps. Also, it is anticipated that the transverse partition members may be formed from continuous strips of proper sheet material fed and appropriately severed and applied by the assembling and gluing machine.

Thus, although in the description of the assembly practice hereinbefore given, and illustrated in FIGS. 1 and 2 to 7, particular reference is made to the use of transverse 25 partition elements of the type shown in FIGS. 1a and 1b, it will be understood that the invention is not limited thereto except as hereinafter particularly claimed, but rather that the assembly practice may be variously modified to adapt it to different requirements, such, for example, as may be dictated by the type of transverse partition members employed and the functional characteristics of a particular assembling and gluing machine.

Various changes and modifications including, and in addition to, those particularly described, are considered 35 to be within the principle of the invention and the scope of the following claims.

What I claim is:

1. In a carrier carton formed from sheet material such as paperboard and of the type capable of being erected 40 from flat-folded condition to cellular form by hinging action of its parts, a bottom wall, side walls extending upwardly from the longitudinal side edges of said bottom wall, end wall elements joined to the opposite ends of said side walls, a combined handle member and longitudinal partition panel disposed medially of and in spaced relation to said side walls and effecting a continuous rigid interconnection between said end walls, said handle member serving to divide the interior of the carton into two spaces longitudinally thereof, partition straps 45 disposed at opposite sides of said handle member and having their opposite ends integral with said side walls and handle member and hingedly connected respectively with said side walls and handle member and extending transversely therebetween to divide each of the said spaces 50 into a plurality of compartments, and a transverse partition member initially separate from the aforesaid carton parts and attached to each of said straps and carried only thereby independently of said side walls and said combined handle member and longitudinal partition panel 55 and extending from the respective straps downwardly into proximity to the bottom wall, said partition members being independently movable with said straps in response to hinging movement of the straps upon erection of the carton.
2. In a carrier carton formed from sheet material such as paperboard and of the type capable of being erected 60 from flat-folded condition to cellular form by hinging action of its parts, a bottom wall, side walls extending upwardly from the longitudinal side edges of said bottom wall, end wall elements joined to the opposite ends of said side walls and provided with complementary connecting flaps joined together medially of the bottom wall to unite said end wall elements in pairs at opposite ends of the bottom and side walls, a handle member disposed 65 medially of and in spaced relation to said side walls

longitudinally thereof and connected in rigid assembly with said connecting flaps at opposite ends of the carton and serving to divide the interior of the carton into two spaces longitudinally thereof, partition straps disposed at opposite sides of said handle member and having their opposite ends integral with said side walls and handle member and hingedly connected respectively with said side walls and handle member and extending there-between transversely of the carton to divide each of the said spaces into a plurality of compartments, a transverse partition member separate from the aforesaid carton parts and attached to each of said straps and carried only thereby independently of said side walls and handle member and extending from the respective straps downwardly into proximity to the bottom wall, said partition members being movable with said straps in response to hinging movement of the straps upon erection of the carton, and a longitudinal partition panel rigidly joined to said handle member and to the said connecting flaps at both ends of the carton and extending from said handle member downwardly into proximity to said bottom wall, said longitudinal partition panel extending medially longitudinally between said side walls in vertical alignment with said handle member, said partition straps, transverse partition members, handle member and longitudinal partition panel serving to provide substantially full depth separation of said compartments.

3. Multipart sheet material flat blank means for a carrier carton of the type capable of being erected from flat-folded condition to cellular form by hinging action of its parts, including a primary blank provided with cuts and folding scores defining a substantially rectangular bottom wall, side walls joined to the longitudinal edges of said bottom wall, end wall sections joined to the opposite ends of said side walls, each of said end wall sections terminating in a connecting flap, complementary ultimately joined handle-forming members offstanding from the ultimate top edges of said side walls, transverse partition straps defined from said side walls and joined thereto and to said handle-forming members at their opposite ends respectively on score means providing hinge connections with said side walls and handle-forming members, and secondary blank means formed as elements initially separate from said primary blank and comprising transverse partition members independent of said side walls and handle-forming members affixed only to said partition straps for hinging movement with said straps and adapted to be carried thereby into disposition transversely of the carton at opposite faces of the ultimately joined handle-forming members by hinging movement of said straps upon erection of the assembled blank to usable form.

4. Carton blank means as defined in claim 3, in which

each of the secondary blank means is an integer including two of said transverse partition members defined from each other by a line of fracture.

5. Carton blank means as defined in claim 4, in which the transverse partition straps of each side wall are arranged in pairs and said secondary blank integer is affixed by one of its partition members to one partition strap of one side wall pair thereof and is thus located upon predetermined folding of said primary blank for attachment of its other partition member to the other strap of said side wall pair.

6. Multipart sheet material flat blank means for a carrier carton of the type capable of being erected from flat-folded condition to cellular form by hinging action of its parts, including a primary blank provided with cuts and folding scores defining a substantially rectangular bottom wall, side walls joined to the longitudinal edges of said bottom wall, end wall sections joined to the opposite ends of said side walls, each of said end wall sections terminating in a connecting flap, complementary ultimately joined handle-forming members offstanding from the ultimate top edges of said side walls, transverse partition straps defined from said side walls and joined thereto and to said handle-forming members at their opposite ends respectively on score means providing hinge connections with said side walls and handle-forming members, secondary blank means formed as elements initially separate from said primary blank and comprising transverse partition members independent of said side walls and handle-forming members affixed only to said partition straps for hinging movement with said straps and adapted to be carried thereby into disposition transversely of the carton at opposite faces of the ultimately joined handle-forming members by hinging movement of said straps upon erection of the assembled blank to usable form, and a partition panel disposed between the ultimate bottom edges of two end wall sections at one end of said bottom wall and freed from said end wall sections and bottom wall by certain of said cuts, said panel being connected to the connecting flap of one of the adjacent end wall sections along a diagonal folding score and being foldable upon such score into flat-folded relation to the adjacent side wall with which the end wall section of its connecting flap is attached.
